UNITED STATES PATENT OFFICE.

FAUSTINO CALDARELLI, OF BOSTON, MASSACHUSETTS.

WIRE-MANIPULATING DEVICE.

Application filed October 11, 1922. Serial No. 593,775.

To all whom it may concern:

Be it known that I, FAUSTINO CALDARELLI, a subject of the King of Italy, and resident of Boston (East Boston), in the county of Suffolk and State of Massachusetts, have invented new and useful Improvements in Wire-Manipulating Devices, of which the following is a specification.

This invention relates to devices for manipulating wire, particularly for tightening stay wires and loops by twisting the strands of the wire or ends of the loops together. One use for which the invention is particularly adapted is the tightening of tie wires or bonds employed in holding together the walls of concrete molds.

One object of the invention is to provide a device of the class described characterized by few parts of sturdy construction and by 20 simplicity and ease of operation so that the ordinary unskilled laborer can operate it. Another object is to provide mechanism by which the operations of gripping, stretching and twisting the wire are performed by 25 rotating the same shaft. A further object is to feed the head forward in proportion to the shortening of the wire produced by the twisting thereof so as to prevent undue strain and possible breakage of the wire. 30 Other objects will be apparent from the detailed description which follows.

In order to illustrate the invention one concrete embodiment thereof is shown in the accompanying drawings, in which:

35 Fig. 1 is a side elevational view partly in section;

Fig. 2 is an end elevational view showing the supporting yoke in section at the bearing for the screw;

40 Fig. 3 is a fragmentary sectional view illustrating one method of supporting a form for concrete floors;

Fig. 4 is a plan view of the usual construction of forms for concrete walls;

45 Fig. 4 illustrates the method of constructing concrete molds practised by building contractors at the present time. The molds comprise facing boards a' and a^2 lightly nailed to longitudinal battens b' and b^2

50 which are generally 2 x 4 scantlings. A gauge stick c is placed within the mold and the walls a' and a^2 are then forced into contact with the gauge stick by wire tension members generally made in the form of a loop d passing through holes in the walls or through openings between the boards form-

ing the walls, and then around two of the battens such as b' and b^2 . Other tension members such as d' may extend at right angles to loops d and may be looped around stringers e' and e^2 which are in parallelism with facing boards a' and a^2 . The wire forming the loops d' may be crossed as shown within the mold.

In Fig. 3 is illustrated a method of supporting molds for concrete floors from the I beams of buildings having a steel frame work. Here the wires forming the tension loops d^2 are looped over the I beam, the ends carried down and looped under the transverse mold support f and then carried up and over the I beam where the ends are twisted together. The work of twisting the ends of the tension loop is frequently difficult when space is limited, and it is not easy to reach the ends of the loop. Sometimes the insertion of wedges under the loop has been resorted to in order to apply the proper tension to the casings of the mold, but this requires skilled workmen and is laborious and time consuming.

The embodiment of the invention disclosed in Figs. 1 and 2 comprises a device for properly tensioning and twisting together the ends of wire loops such as d , d' and d^2 of Figs. 3 and 4, which can be operated by an unskilled laborer with a minimum of time and trouble. The device comprises a heavy yoke 5 adapted to rest at its ends against the outer face of one of the 90 battens such as b^2 of Fig. 4, and to be held in place by offset extensions 6 having driving points 7. These driving points are arranged to be driven into the upper edge of the batten.

Centrally in yoke 5 in a screw threaded opening 8 is a screw 9 having an operating handle 10 at one end, and a flanged head 11 at the other end. Engaging the flanged head 11 and rotatable thereon is a chuck comprising a casing 12 and a cone member 13 within which two pivoted jaws 14 can be wedged to engage with each other; and also comprising an internal nut 15 serving as a retainer for casing 12 on the flanged head 11, 100 into which nut takes a screw threaded extension 16 of the yoke bearing 17 for the pivot of jaws 14.

The cone member 13 of the chuck has a collar 18 fastened thereon, said collar extending beyond the member and having a close sliding fit over casing 11. Pivoted for

rotative movement on collar 18 by means of a screw bolt 20, the shank of which serves as a pivot, is a lever 21 adapted to be swung to a position at right angles to the axis of shaft 9 to engage one of the legs of yoke 5 and stop the rotation of the cone member 13 with the chuck.

Suitable means are provided for causing the chuck to rotate with the screw 9. One 10 form of means for accomplishing this purpose comprises a clutch consisting of a pivoted spring pressed member or dog 22 mounted in a slot 23 in screw shaft 9 adjacent flanged head 11, and a rotatable barrel 15 cam 24 in the form of a collar encircling the end of screw shaft 9 between the casing 12 of the chuck and a retainer 25 on the shaft. Member or dog 22 cooperates with suitable teeth 26 on casing 12 and is controlled by a 20 wave cam surface 27 in cam member 24, the elevations of the cam surface being diametrically opposed to the depressions thereof as indicated in Fig. 1.

Proper manipulation of lever 21 permits 25 the operation of the jaws 14 to be controlled by shaft 9. If lever 21 is in engagement with yoke 5 to stop the rotation of chuck member 13, and clutch member 22 is in engagement as shown in Fig. 1, rotation of shaft 9 will produce relative movement of parts 12 and 13 of the chuck. If the motion of the shaft 9 is counter-clockwise the jaws 14 will grasp and withdraw or stretch the wire d. If the lever 21 is then moved to the 30 position shown in Fig. 1, the whole structure supported on shaft 9 will rotate in whatever direction the shaft is turned. If this direction is clockwise the ends of wires d will twist together and the chuck holding them 35 will move toward the batten b² on which the yoke is positioned. The pitch of screw 9 is chosen to correspond to the twist pitch of the twist t of wires d of standard size. Therefore the twisting together of the wires 40 d takes place without substantial change of the tension of the runs of the loop d attained when the chuck was backed off during the counter-clockwise rotation of shaft 9.

The operation of the device includes 45 positioning the yoke 5 upon the batten, forcing points 7 into the batten to hold the yoke, setting up the chuck jaws 14 by moving lever 21 to the position where it engages the yoke 5 and rotating shaft 9 slightly in 50 counter-clockwise direction, restoring lever 21 to its original position, then unlocking the clutch by a slight rotation of cam member 24, and applying tension to wires d by 55 backing off the chuck by counter-clockwise rotation of shaft 9, the chuck not rotating with the shaft by reason of the throwing out of the clutch. When the proper tension has been impressed from the loop d, 60 the clutch is again thrown into operation by moving cam 24, and then the shaft 9 is ro-

tated in a clockwise direction to twist the ends of wire d together while the clutch jaws 14 move inwardly to compensate for further stress due to the twisting together of the wires.

From the above it will be apparent that the apparatus herein disclosed comprises few parts of great strength, that the device can be easily and efficiently operated by an ordinary laborer, and that all of the operations of the device including gripping the wire, applying initial tension to the loop by backing away the clutch, and the final operation of twisting the ends of the wires together, are effected through the rotation of screw shaft 9 in the proper direction after the proper adjustments of lever 21 and clutch control member 24 are manually made.

I claim:—

1. The combination of a supporting member, a screw mounted in a threaded bearing in said member, a wire gripping device mounted to rotate on the end of said screw, and means for clutching said device to said screw to rotate therewith.

2. The combination of a supporting member, a screw mounted in a threaded bearing in said member, a wire gripping device rotatably mounted on the end of said screw, including movable jaws, and means for closing said jaws together on reverse rotation of said screw.

3. In apparatus for tightening stay wires for concrete forms, in combination, a supporting member adapted to rest upon the concrete form, a screw mounted in a threaded bearing in said member, wire gripping jaws on one end of said screw, and means whereby rotation of said screw may be utilized selectively to close said jaws together, to retract said jaws from the form in order to stretch the wires, and to tighten the wires by twisting the ends thereof together while concomitantly feeding the twisted ends of the wire toward the form.

4. In apparatus for tightening stay wires for concrete forms, in combination, a supporting member adapted to rest upon the concrete form, a screw mounted in a threaded bearing in said member, a chuck on one end of said screw having gripping jaws, and means on said chuck adapted to engage said member to hold the chuck against rotation when said jaws are to be closed together or loosened whereby said screw may be rotated for the purpose of operating said chuck.

5. A wire manipulating device for setting up wire bonds under tension and locking the bonds by twisting the wire ends together having therein a gripper head, a screw shaft for the head and a clutch connection between head and shaft, whereby the head may be caused to seize and back off with the ends

of the bond without twisting, and may be caused to twist the ends of the bond while moving the head in accordance with the shortening of the bond due to twisting.

6. In apparatus for tightening stay wires for concrete forms, in combination, a supporting member adapted to rest upon the concrete form, a screw mounted in a threaded bearing in said member, a chuck on one end of said screw having gripping jaws, and a clutch interposed between said screw and chuck.

7. In apparatus for tightening stay wires for concrete forms, in combination, a supporting member adapted to rest upon the concrete form, a screw mounted in a threaded bearing in said member, a chuck on one end of said screw having gripping jaws, a clutch interposed between said screw and chuck, and means for manually controlling said clutch.

8. In apparatus for tightening stay wires for concrete forms, in combination, a supporting member adapted to rest upon the concrete form, a screw mounted in a threaded bearing in said member, a chuck on one end of said screw having gripping jaws, a clutch interposed between said screw and chuck and a cam device rotatable on said screw for manually controlling said clutch.

9. In combination, a supporting member, a screw mounted in a threaded bearing in said member and having a flanged end, a chuck having gripping jaws rotatably mounted upon said flanged end of said screw, and means for selectively clutching said chuck to said screw.

10. In combination, a supporting member, a screw mounted in a threaded bearing in said member and having a flanged end, a

chuck having gripping jaws rotatably mounted upon said flanged end of said screw, and means for independently and selectively clutching said chuck to said screw including a pivoted dog on one of said last named elements arranged to engage teeth on the other.

11. In combination, a supporting member, a screw mounted in a threaded bearing in said member and having a flanged end, a chuck having gripping jaws rotatably mounted upon said flanged end of said screw, and means for selectively clutching said chuck to said screw including a dog pivoted in a slot in said screw for engagement with teeth on said chuck, and a cam device for controlling said dog.

12. In combination a support, a screw mounted in a threaded bearing in said support, said screw having a flanged end, a chuck on said screw comprising a casing engaging said flanged end, a conical member on said casing, gripping jaws in said conical member, and a member arranged to retain said casing in place and said jaws within said conical member.

13. In combination, a support, a screw mounted in a threaded bearing in said support, said screw having a flanged end, a chuck on said screw comprising a casing engaging said flanged end, a conical member on said casing, gripping jaws in said conical member, a retainer for said casing, and means associated with said retainer and said jaws for adjusting said jaws on relative movement of said casing and conical member.

Signed by me at Boston, Massachusetts, this seventh day of October, 1922.

FAUSTINO CALDARELLI,
